CLAIM

We claim the ornamental design for a dry erase board, as shown and described.

DESCRIPTION

FIG. 1 is a perspective view showing a new design for a dry erase board;

FIG. 2 is a front view of the dry erase board of FIG. 1;

FIG. 3 is a rear view of the dry erase board of FIG. 1, the rear view thereof is unornamented;

FIG. 4 is a side view of the dry erase board of FIG. 1, the opposite side view is identical; and,

FIG. 5 is a top plan view of the dry erase board of FIG. 1, the bottom plan view is identical.

The stippling shown on the display board in FIGS. 1 and 2 represents a contrast of materials.

The broken lines in FIG. 3 represent the rear surface and form no part of the claimed design.
